UNITED STATES PATENT OFFICE.

FRANK HEYARD, OF CANTON, OHIO, ASSIGNOR TO THE BERGER MANUFACTURING COMPANY, OF SAME PLACE.

HURRICANE-LANTERN.

SPECIFICATION forming part of Letters Patent No. 624,933, dated May 16, 1899.

Application filed February 10, 1899. Serial No. 705,143. (No model.)

To all whom it may concern:

Be it known that I, FRANK HEYARD, a citizen of the United States, residing at Canton, in the county of Stark and State of Ohio, have 5 invented new and useful Improvements in Tubular or Hurricane Lanterns, of which the following is a specification.

My invention relates to improvements in tubular or hurricane lanterns; and it consists 10 of certain features of construction and combination of parts by which the combined globe-carrying frame and the annular spring- 15 catch formed of a single piece of wire has formed upon one of the limbs thereof a shifting link, and also in providing a lever attached to the lower end of one of the vertical air-tubes, one end of which engages the shifting link formed on the globe-carrying frame and the other having formed thereon a thumb- 20 piece by which the same is operated, as will be hereinafter more fully set forth and described.

Figure 1 is a perspective view of a tubular lantern, showing the combined globe-carrying frame, annular spring-catch, shifting link, and raising and lowering lever applied thereto and showing the position thereof when the globe-carrying frame is raised. Fig. 2 is a perspective view of the combined globe-carrying frame, annular spring-catch, and shifting link. Fig. 3 is a perspective view of the lower right-hand side of the lantern, showing the position of the lever and shifting link when the globe-plate is lowered in 35 its normal position.

Similar letters of reference refer to similar parts of the several drawings.

A represents the oil-pot of the lantern, upon which are mounted the air-chamber B and 40 burner C. To the air-chamber B and on either side thereof are attached horizontal air-tubes, connecting with the vertical side tubes, which in turn connect with the horizontal tubes at the top of the lantern, terminating in the centrally-depending air-tube D, carrying the sliding bell E, to which is attached the combined globe-carrying frame, annular spring-catch, and shifting link, formed of a single piece of wire.

50 The combined globe-carrying frame, annu-

lar spring-catch, and shifting link is formed of a single piece of wire, the free ends f and f' of which engage with or are soldered to the globe-plate G and pass up on either side of the globe through guide-loops H and I upon the inner side of the vertical side tubes, and are held in engagement with the bell E by means of small wire loops reamed in the edge of the bell, and thence continue to the rear of the bell and are bent downward and inward and thence around the globe to the front of the lantern and upward, forming a lifting handle or grip f''. Upon the lower end f there is formed a shifting link f''' by bending the wire out at right angles to the vertical limb and thence back and upward. The advantage of this new and novel construction is that the shifting link is formed by the same device and of the same material as the globe-carrying frame, and the shifting link thus 55 being located nearer the vertical tube, to which is attached the lever, the distance between the fulcrum and the weight is thus 60 materially decreased and the globe-carrying frame is more readily operated. The lifting- 65 lever engaging with the shifting link, which is not in direct contact with the globe-frame or burner, does not become heated; but, on the contrary, the air is permitted to and does 70 pass about the shifting link and the lifting- 75 lever in such a manner as to keep them constantly cool.

Upon the vertical air-tube there is journaled a lifting-lever J at the right side of the lantern, the inner end of which engages with 80 and slides in and upon the shifting link f'''. Upon the free end of the lifting-lever there is formed a thumb-piece j to facilitate in the 85 operation of the lever, the free end of the lever projecting out from the point at which 90 it is journaled upon the vertical tube a sufficient distance to enable it to be swung up and down, but at the extreme limit of either movement to rest upon or against the vertical tube. Upon the inner end of the lever 95 there is soldered a metallic washer j'', which acts as an additional guide in the movement of the inner end of the lever in the shifting link.

In operation the lever J is turned com- 100

pletely down, and the motion is transmitted through the shifting link to the globe-carrying frame, and the globe-plate and globe are caused to rise and the bell to slide upon the 5 depending central tube, and the lever having completed its full stroke securely holds or locks the lever in its open position. To close the lantern after lighting, the lever J is turned completely up against the vertical 10 tube, and the motion is transmitted through the shifting link to the various parts, which are then lowered to their normal position, closing the lantern.

Having thus fully described my invention, 15 what I desire to secure and claim by Letters Patent is—

1. A combined globe-carrying frame, an annular spring-catch formed of a single piece of wire, and having formed upon one of its 20 lower limbs a shifting link for engagement with an operating-lever journaled in the vertical frame of the tubular lantern, substan-

tially as described and for the purpose set forth.

2. The combination in a tubular lantern, 25 of an operating-lever journaled to the vertical tube, the inner end thereof having a sliding connection with a shifting link formed upon the lower end of the globe-frame, substantially as described and for the purpose 30 set forth.

3. In a tubular lantern, a globe-frame formed of a single piece of wire, and having formed upon the lower end of one of its limbs a shifting link for engagement with an operating-lever, substantially as described and for the purpose set forth.

In testimony whereof I have hereunto set my hand in the presence of two subscribing witnesses.

FRANK HEYARD.
